UNITED STATES PATENT OFFICE.

IRVING H. VAN HORN AND WILBUR A. PIPKIN, OF EAST CLEVELAND, OHIO, AS-SIGNORS TO GENERAL ELECTRIC COMPANY, A CORPORATION OF NEW YORK.

AUTOMATIC CUT-OUT FOR ELECTRIC INCANDESCENT LAMPS.

Application filed March 11, 1924. Serial No. 698,502

Our invention relates to series electric incandescent lamps and more particularly to means for preventing the extinguishment of all the lamps in the series upon the failure 5 of any one lamp. Heretofore one way of taking care of this situation was to arrange the conducting supports of the filament so that portions thereof were very close together. It was necessary to have the conductors close enough together so that upon 10 a failure of the filament during use and the consequent arcing that the molten mass produced by the fusing of the filament supporting conductors would bridge the gap 15 therebetween and provide a conductive path through the lamp which would preserve the circuit for the other lamps of the series and thus prevent their extinguishment. On the other hand it was necessary to separate the 20 conductors far enough so that there would normally be no arcing which would short circuit the filament. In order to fix this distance it has been considered desirable to provide an insulating separator engaging 25 and holding the conducting supports at a definite distance apart. While such an arrangement takes care of the condition created by the failure of a lamp during use, it does not take care of the condition created by 30 the failure of a lamp when not in use. Such a failure results in the lamps subsequently failing to light and there is inconvenience in locating the particular lamp which is causing the trouble. Our invention provides 35 means for taking care of both of the aforesaid conditions for, according to our invention, the device which spaces the conductors, while normally insulating, becomes conductive if there is a broken filament in the device when the current is turned on. 40

In the drawing, Fig. 1 is an elevation of a series electric incandescent lamp; Fig. 2 is a side elevation of parts thereof; Fig. 3 is a partial elevation of such a series electric 45 incandescent lamp in which the filament has been broken; Fig. 4 is an elevation of a portion of a lamp showing the operation of our invention under one condition; Fig. 5 is a partial horizontal section showing our 50 improved separator or cut-out; Fig. 6 is a perspective thereof; and Fig. 7 is a vertical section thereof.

As shown in Fig. 1, the incandescent lamp 55 comprises the bulb 10 having the usual base 11 and stem 12 in which are sealed the lead-

ing-in conductors and filament supports 13 and 14. The filament 15 is mounted at the ends of the supports 13 and 14. In Figs. 5, 6 and 7 are shown the spacing member 16 which is shaped to engage the filament conducting supports 13 and 14. Preferably this member is a so-called film cut-out and is composed of sheet aluminum 17 coated with a thin film of aluminum oxide 18. This coating may be accomplished electrolytically or by other well-known methods. The cut-out is mounted so as to closely engage the conductors 13 and 14 and is bent around the conductors, preferably in the form shown, so that it rigidly maintains its 70 position.

In Fig. 3 the filament 15 is shown to be broken. When this happens while the lamp is in use, an arc will form between the conductors 13 and 14 and gradually fuse the said conductors forming globules of molten metal which finally coalesce as shown in Fig. 4, when they reach the separator 16. This provides a conductive path through the lamp completing the circuit for the other lamps in the series and prevents their extinguishment.

If the filament 15 breaks when the lamp is not in use, the film cut-out operates when the circuit switch is closed. The full voltage of the line being across the film cut-out, the film of aluminum oxide is punctured and a conductive path provided. This allows the other lamps of the series to light up and at the same time shows up the defective lamp.

It will be obvious that various film cut-outs may be substituted for that specifically hereinbefore referred to.

What we claim as new and desire to secure by Letters Patent of the United States, is:

1. In an electric incandescent lamp, the combination of a bulb containing a non-oxidizing atmosphere, a filament mounted within said bulb, a stem sealed within said bulb, a pair of conductive supports for said filament sealed in the inner end of said stem, and a member consisting of a conductive support having thereon a coating of insulation adapted to be broken down under abnormal conditions mounted between said supports and within said bulb, said member serving to hold the said conductive supports in close proximity to each other.

2. In an electric incandescent lamp having terminals, the combination of a filament sur-

rounded by a non-oxidizing atmosphere, a pair of conductive supports therefor connected to the lamp terminals, and an oxide coated conducting member disposed between 5 said portions and serving to hold portions of said conductive supports in close proximity to each other.

3. In an electric incandescent lamp having terminals, the combination of a filament 10 consisting of a single strand surrounded by a non-oxidizing atmosphere, a pair of con-

ductive supports therefor connected to the lamp terminals, and an oxide coated conducting member disposed between said portions and serving to hold portions of said 15 conductive supports in close proximity to each other.

In witness whereof, we have hereunto set our hands this 8th day of March, 1924.

IRVING H. VAN HORN.
WILBUR A. PIPKIN.
